UNITED STATES PATENT OFFICE.

LESLIE HAROLD FRIEDMAN, OF ST. KILDA, MELBOURNE, VICTORIA, AUSTRALIA.

SPRING-MOTOR-OVERWINDING PREVENTER.

1,109,569.

Specification of Letters Patent.

Patented Sept. 1, 1914.

Original application filed February 12, 1912, Serial No. 677,064. Divided and this application filed November 15, 1912. Serial No. 731,502.

To all whom it may concern:

Be it known that I, LESLIE HAROLD FRIEDMAN, a subject of the King of Great Britain and Ireland, previously residing at 268 5 Albert street, in the post-town of East Melbourne, a suburb of the city of Melbourne, in the county of Bourke, State of Victoria, Commonwealth of Australia, and later at "Killeen," Grey street, but now at 32 Car- 10 lyle street, both in the city of St. Kilda, a suburb of the city of Melbourne aforesaid, have invented certain new and useful Im- 15 provements in and relating to Spring-Motor- Overwinding Preventers, of which the following is a specification.

This invention relates to means for preventing the over-winding of tension springs used, for example, in the spring motor de- 20 vices employed for operating the sliding car- 25 riages of typewriting machines, and covers subject matter divided from my prior ap- plication, Serial Number 677,064, filed Feb- 30 ruary 12, 1912.

Although particularly applicable to the 25 tension springs of typewriting machines the invention is not limited thereto and may be employed in other capacities, its main ob- ject being to govern the spring tension and prevent overwinding of the said spring when 30 winding thereof is effected automatically.

Referring to the drawings which form part of this specification:—Figure 1 is a rear perspective view of a typewriting machine showing the present invention applied to the 35 invention disclosed by my prior United States application Serial No. 677064 afore- mentioned. Fig. 2 is a perspective view showing this invention applied to the re- versing mechanism of my prior invention 40 aforementioned. Fig. 3 is a view of this in- vention by which the spring tension is gov- erned. The arrows indicate the direction of travel of an axle when the spring is being wound. The recoil of the axle and a ratchet 45 wheel secured thereto is in the opposite di- rection to that indicated by the arrows. Fig. 50 4 is a back or rear view to show the connec- tion to the carriage, by tapes, of the revers- ing mechanism comprising my prior inven- tion. The arrows indicate the direction of 55 movement of various parts when a line is be- ing written and the tension spring is being automatically wound. Fig. 5 is an end part sectional view of the reversing mechanism.

contained in my prior invention aforemen- 55 tioned. Fig. 6 is a view of mechanism op- erated by each depression of the keys and which itself operates the mechanism seen in Fig. 3 for maintaining the tension of the 60 spring moving the carriage.

The typewriting machine includes a framework 2, having a right hand end 3, and a left hand end 4. Slidably carried by the framework is a carriage 5 of any suitable construction. The carriage is controlled by a ribbon tension spring hereinafter more 65 fully referred to. The tension spring is intermittently released by the depression of keys as is usual, the carriage moving from the right toward the left hand end of the 70 framework each time a key is depressed. Any suitable and common form of escape- ment mechanism for intermittently permitting the carriage to move may be employed. Beneath the key levers of the machine and 75 extending across the framework is a cross bar 8. Secured to the rear of the carriage 5, and extending from one end thereof to the other, is a stop bar 66. Embracing the stop bar 66 is a reversing stop 70. Embracing the 80 said stop bar is also a reengagement stop 75.

Upstanding above the right hand end of the rear of the framework is a plain bearing 79. Upstanding above the left hand end of the rear of the framework is a bearing 80. 85 Mounted in the bearings 79 and 80 is a re- versing bar 86 having a rack 94. Engaging the rack 94 of the reversing bar is a pinion 103 mounted at the top of a spring con- trolled vertical spindle 104. At the lower 90 end of the vertical spindle 104 is a crank pin 106 engaging an intermediately pivoted lever 108 operating a slide 112. Adjoining the slide 112 is an inner clutch lever 113. This is pivoted by a pivot pin 114, at its 95 upper end, to the rear of the left hand end of the framework. Adjoining the slide 112 is also an outer clutch lever 116. This is pivoted, by a pivot pin 117, at its upper end, to the rear of the left hand end of the frame- 100 work. Extending between the clutch levers 113 and 116 is a contracting spring 119. Be- 105 tween the clutch levers is a driving drum 120, having inner teeth 121 and outer teeth 122. Within the driving drum is a coiled ribbon tension spring 123. One end—the outer end—of this is secured to the interior of the drum while the other or inner end is

secured to an axle 124. The said axle is provided with a finger turner 125 by which the spring may be wound.

Adjoining the driving drum and between 5 the same and the inner clutch lever 113 is an inner clutch drum 126, having teeth 127. The drum 126 is loosely mounted on the axle 124. Secured to the circumference of the inner clutch drum 126 is the winding end 130 of a first tape 131. The other or carriage end 132 of the said first tape is secured to the right hand end of the carriage 5.

Between the driving drum 120 and the outer clutch lever 116 is an outer clutch drum 133 having teeth 134. The drum 133 is loosely mounted on the axle 124. Secured to the circumference of the said drum 133 is the winding end 135 of a second tape 136. The other or cam end 137 of the said tape 136 is 20 secured to the circumference of a cam 138. The cam 138 is mounted upon the outer end of a spindle 139 mounted upon the inner end of which is a wheel 140. Secured to the circumference of the wheel 140 is the winding 25 end 141 of a third tape 142. The other or carriage end 143 of the third tape 142 is secured to the left hand end of the carriage 5.

Mounted upon the axle 124 is a ratchet wheel 144. Loosely accommodated by the 30 said axle 124 are also the inner ends of a forked lever 145 having an inner and an outer arm, one each side of the said ratchet wheel. The inner arm of the said lever is provided with an extension 146 and is therefore intermediately pivoted to the axle 124. Pivoted to the said lever by a pivot pin 147 is a pawl 148 controlled by a spring 149. Controlling the lever 145 is also a lifting spring 150.

40 Protruding or forming part of the framework, adjacent the extension 146, is a guide 151. Accommodated by the guide 151 is a slide 152 carrying a screw 153. Accommodated by the screw 153 and bearing against 45 a portion of the framework, or an extension thereof, is a nut 154. Secured to the slide 152 is one end of a spring 155. Pivoted to the framework, or an extension thereof, by a stud 156, is a crank lever having a short 50 arm 157 and a long arm 158. To the short arm 157 is attached the other end of the spring 155. Pivoted to the framework, or an extension thereof, by a stud 159, is a disengaging tappet 160, (not engaging the 55 wheel 144), provided in its boss with a recess 161. The end of the long arm 158 of the crank lever is accommodated by the recess 161 the said recess being of sufficient area to freely or loosely accommodate the 60 said end. Pivoted by a pivot pin 162 to an extension of the long arm 158 of the crank lever is a holding pawl 163 controlled by a spring 164. The long arm is, therefore, as shown, in fact an intermediately pivoted 65 lever.

Pivoted by a pivot pin 165 to the outer end of the lever 145 is the upper end of a connecting rod 166. Pivotedly connected to the lower end of the connecting rod 166 is the rear end of a first intermediately pivoted lever 167. The said lever by a stud 168 is pivoted to the left hand end of the framework. The front end of the lever 167 engages with a roller 169 carried by the rear end of a second intermediately pivoted lever 170. The second lever 170 is attached to the left hand end of a spindle 171 extending across the framework beneath the key levers 7. At its right hand end the spindle 171 is provided with a lever 172. Pivoted by pivot pins 173 to the levers 170 and 172 is the cross bar 8. Depending from the cross bar 8 are lugs 174 to which are pivotally connected the rear ends of links 175, the front ends of which are pivoted to the framework or an extension thereof. The said links 175 may be controlled by a spring 176.

The cycle of operations with this invention is as follows:—Upon each depression of a key 6 or its equivalent any suitable escape- 80 ment mechanism permits the carriage 5 to move a certain distance from right to left as in an ordinary typewriting machine. The inner clutch drum 126 is now in engagement with the driving drum 120 which is rotated by its tension spring 123. The inner clutch drum 126 is therefore being driven by the driving drum 120. The drum 126 draws with it, each time a key is depressed and it is permitted to travel, the winding end 130 85 of the first tape 131. On account of the carriage end 132 of this tape being attached to the right hand end of the carriage 5 the said carriage moves in the direction indicated, i. e. from right to left. Upon the carriage 5 reaching the end of a line the reversing stop 70 frees the reversing bar permitting the spring controlling the pinion 103 in engagement with the rack 94 of the reversing bar 86 to assert itself and by its tension rotate the 90 pinion and move the said bar from right to left. As the pinion 103 rotates, or partially rotates, it will be seen that the vertical spindle 104, must also partially rotate, and, by the crank pin 106 and intermediately pivoted 95 lever 108, operate the slide 112. This, by the pivoted clutch levers 113 and 116, throws the inner clutch drum 126 out of engagement and the outer clutch drum 133 into engagement with the driving drum 120. Immediately this occurs the tension spring 123 100 within the driving drum 120 drives the outer clutch drum 133, which, by the second tape 136 moves the cam 138 in the opposite direction to that indicated by the arrows 105 shown in Fig. 4. The cam 138 turns the spindle 139 upon which it is mounted and therefore also turns the wheel 140 to which is attached the winding end 141 of the third tape 142. On account of the carriage end 110 115 120 125 130

143 of this tape being attached to the left hand end of the carriage 5 the said carriage moves in a reverse direction to that which it previously traversed—that is—from left to right, and thus the said carriage is returned to the position which it first occupied.

As the carriage returns the reengagement stop 75 returns the reversing bar to its initial position. As the reversing bar 86 moves from left to right it will also be apparent that the pinion 103 is rotated by the rack 94. This turns the spindle 104 and crank pin 106. By the movement of the crank pin the intermediately pivoted lever 108 operates the slide 112. This by the clutch levers 113 and 116 throws the outer clutch drum 113 out of engagement and the inner clutch drum 126 once more into engagement with the driving drum 120. The carriage may once more move now, from right to left, the various parts being set to return the carriage at the end of a line as already described.

With each depression of a key lever it will be clear that the cross bar 8 beneath the said key levers is depressed. This, by the levers 170 and 167 described, operates the connecting rod 166. The rod 166 in turn draws downwardly the outer end of the lever 145 adjacent the ratchet wheel 144. With the lever moves the pawl 148 which being in engagement with the teeth of the ratchet wheel partially rotates the said wheel. The spring 150 returns the said lever 145 after each such movement and the holding pawl 163 before described prevents escapement of the said ratchet wheel 144. It will therefore be plain that as the carriage 5 moves from right to left the depression of the keys 6 operates the ratchet wheel 144 rotating the axle 124 upon which it is mounted. As one end of the tension spring 123 is secured to the axle 124 the rotation of the axle winds the said tension spring 123 within the driving drum 120 and maintains or gathers up the tension of the said spring which was lost in returning the carriage at the end of the line previously written. It should be explained that the tension of the spring 123 during the operation just described is comparatively low or, in any case, is not high. That is to say the spring is not fully wound, and, therefore, the pawls 148 and 163 have no difficulty in operating the ratchet wheel 144 as the recoil or tendency to unwind of the spring 123 and the tendency of the ratchet wheel 144 to recoil or follow the said spring is not severe or great.

The finger turner upon the axle 124 may of course be used to wind the tension spring 123 should it be desired. The automatic winding of the spring 123 has been described but should the tension upon the said spring be for any reason too severe, or when the said spring reaches a certain ten-

sion a continued automatic winding of the said spring is automatically prevented. Therefore should the tension of the spring 123 run down or weaken to any material extent the said tension spring is automatically rewound as described and when, under any circumstances, sufficient tension has been obtained the winding mechanism is automatically thrown out of gear as will now be explained. It should be understood that when axle 124 is stationary the tendency of the spring 123 is to rotate the driving drum 120 in one direction but when the drum 120 is stationary the tendency of the spring is to rotate the axle 124 and with it the ratchet wheel 144 in the opposite direction. When the spring 123 is normally wound the ratchet wheel 144 will therefore have what may be termed a normal recoil but when the condition of the spring 123 tends toward over-winding the recoil of the ratchet wheel 144 will be abnormal or severe. It is obvious, then, that when the recoiling action reaches a certain stage or is abnormal the holding pawl 163 will be slightly lifted with each recoiling movement of the ratchet wheel 144. The direction of the recoil of the ratchet wheel is the opposite to that indicated by the arrows in Fig. 3. When the pawl 163 is so lifted it is clear that the long arm extension to which the pawl 163 is pivotally attached must also be lifted. The long arm 158 being actually an intermediately pivoted lever the end of it in engagement with the recess 161 of the tappet 160 now descends in the said recess and strikes its bottom or lower edge comparatively sharply. This has the effect of moving the upper end of the tappet 160 inwardly and beneath the extension 146 of the inner arm of the lever 145. As before described with each downward movement of the connecting rod 166 the outer end of the lever 145 to which the said rod 166 is pivotally connected also descends carrying downwardly the pawl 148 which in consequence operates the ratchet wheel 144. The direction of travel of the ratchet wheel when this takes place is indicated by the arrows shown in Fig. 3. The descent of the one end of the lever 145 elevates the extension 146. The lever 145, when a key or the like which caused its descent is released, is lifted by the spring 150. If the upper end of the tappet 160 has moved inwardly and is poised beneath the extension 146 it follows that the said extension cannot fall to its full extent and the spring 150 therefore cannot lift the pawl 148 sufficiently to enable it to engage another tooth of the ratchet wheel 144. The automatic winding mechanism is therefore out of gear. When the parts referred to are in this condition the spring 150 cannot lift the pawl 148 and the outer end of the lever 145 to their normal position and

therefore the connecting rod 166 is slightly depressed. This has the effect of slightly lowering the rear end of the lever 167 and consequently slightly elevating the front end of the said lever from the friction roller 169. This however has no detrimental or other effect. It may be mentioned, too, that with each movement of the ratchet wheel 144 by the pawl 148 the pawl 163 is slightly depressed. This has the effect of lowering the extension of the long arm 158 and bringing its other end into engagement with the top or upper edge of the recess 161. This throws the upper end of the tappet 160 outwardly or away from the extension 146. When the recoil of the ratchet wheel 144 is normal the outward movement of the tappet 160 is an idle one incidental to the mechanism but not a necessity. When the recoil of the ratchet wheel 144 is abnormal the end of the long arm 158 will be given its maximum stroke from the top to the bottom of the recess 161 through this idle movement. The consequence is that the tappet 160 moves very quickly when the recoil is abnormal and is always then in position in time to prevent the extension 146 completing its full journey, as described. By turning the nut 154 the slide 152 is moved and the tension of the spring 155 upon the short arm 157 of the crank lever either lessened or increased. The end of the long arm 158 may thereby be engaged with either the top or bottom edge of the recess 161. In addition when the recoil of the ratchet wheel 144 is abnormal the tension of the spring 155 has to be overcome by the recoil and regulating or timing of the moment when the tappet 160 will come into complete operation 40 may thus be effected.

Having now described my invention what I claim as new and desire to secure by Letters Patent is:—

1. The combination with a tension spring of means for applying a winding movement to the spring, means adapted to be actuated to render said winding means inoperative, an adjustable resilient device normally holding the second mentioned means out of action, and means operated by the spring at a predetermined tension for setting into operation said second mentioned means against the resistance of said resilient device.
- 55 2. The combination with a tension spring of means for applying a partial winding movement to the spring, a pawl and ratchet mechanism for retaining the spring against recoil, a device for rendering said means inoperative, and means operated through said pawl and ratchet mechanism by a predetermined tension on the spring for actuating said device.
- 60 3. The combination with a tension spring having one end fixed of a ratchet wheel se-

cured to the other end of the spring, a pawl for operating said ratchet wheel and means actuated by the recoil of the ratchet wheel for arresting the operation of the pawl when the spring has acquired a predetermined tension. 70

4. The combination with a driving drum of a tension spring within said drum, an axle secured to the spring, a ratchet wheel secured to one of said parts, means for actuating said ratchet wheel, a trip pawl adapted to be actuated to render said means inoperative, means for actuating said trip pawl, operated by the recoil of the ratchet wheel, when the spring reaches a predetermined tension, and means for preventing operation of said trip pawl by its actuating means until said predetermined tension is reached. 75

5. The combination with a tension spring of an axle controlled by said spring, a ratchet wheel secured to said axle, a lever having an extension intermediately pivoted to said axle, a pawl carried by said lever at one end engaging said ratchet, a spring lifting said lever at its pawl end and depressing the extension, and means actuated by the recoil of the ratchet wheel when the spring reaches a predetermined tension for preventing the depression of said extension. 80

6. The combination with a tension spring of an axle controlled by said spring, a ratchet wheel secured to said axle, a pawl engaging said ratchet wheel, a lever carrying said pawl and pivotally supported by said axle, an extension on said lever, a connecting rod for actuating said lever in one direction, a spring for actuating said lever in the opposite direction, a holding pawl engaging said ratchet wheel, a crank lever carrying said holding pawl, a trip pawl adjacent said crank lever and adapted to engage said extension, and a recess in said pawl engaged by said crank lever. 95

7. The combination with a tension spring, of a ratchet wheel for winding the spring, pawl mechanism for applying a winding movement to said ratchet wheel, a spring controlled holding pawl engaging said ratchet wheel, and means operated by said holding pawl by a predetermined force of recoil of said ratchet wheel for rendering said pawl mechanism inoperative. 110

8. The combination with a tension spring, of a reciprocating pawl device for winding said spring, and means operated by a predetermined degree of tension upon the spring for preventing the reciprocations of said pawl device. 115

9. The combination of a tension spring, a ratchet wheel controlling said spring, a spring controlled rocking lever carrying a pawl engaging said ratchet wheel, means for operating said rocking lever, a holding pawl engaging the ratchet wheel, adjust- 120

130

able resilient means for controlling said holding pawl, and means operated by said holding pawl when the spring has acquired a predetermined tension for restraining the movement of said rocking lever.

10. The combination of a tension spring, a ratchet wheel controlling said spring, pawl mechanism for operating said ratchet wheel, a pivotally mounted holding pawl for said ratchet wheel and movable thereby when the spring reaches a predetermined tension, an adjustable spring device con-

nected to said holding pawl, and means operated by a predetermined amount of movement of said holding pawl against the action of said spring device for preventing the operation of said pawl mechanism. 15

In testimony whereof I affix my signature in presence of two witnesses.

LESLIE HAROLD FRIEDMAN.
